UNITED STATES PATENT OFFICE

CHARLES G. HAYES, OF CHICAGO, ILLINOIS, ASSIGNOR TO CHICAGO CARTON COMPANY,
OF CHICAGO, ILLINOIS, A CORPORATION OF ILLINOIS

PRINTING PLATE AND METHOD OF MAKING THE SAME

Application filed April 5, 1930. Serial No. 441,746.

The invention relates to printing plates having screen-formed or half-tone printing surfaces, and seeks to provide an improved plate of this sort and a simple, convenient method of forming the same.

The usual half-tone plate has its printing surface all in a common plane with "high lights", "dark tones", and "intermediate tones" formed by varying the size of the screen dots or figures. With such plates, and particularly when "high lights" form the edge portions of its printing surface, heavy blurred lines are apt to be formed in the printing operation by the edges or edge portions, and such defects are not readily and properly corrected by the usual "make ready" methods.

The present invention seeks to provide a plate having a half-tone or screen-formed printing surface which will not blur in the printing operation along the edge of its printing surface, and to avoid this defect a plate is provided in which its metal body is slightly depressed along the edges of its printing surface, or along such edge portions as are formed by "high lights." In accordance with the improvement, the plate is first made in any usual way by electrotyping or other process which provides a half-tone or screen-formed printing surface. Then the metal of the plate on its under side is cut away or grooved beneath the edges of the printing surface, or beneath such portions of the edges as are formed by or border upon "high lights", and such edges or edge portions are then slightly depressed by applying pressure with a suitable blunt tool or tamping device to the upper surface of the plate along a line closely adjacent, but outside, the edge portion of the printing surface.

The foregoing features of the invention are hereinafter more fully set forth, and one embodiment of the improved plate is illustrated in the accompanying drawings, and the invention is particularly defined in the appended claims.

In the drawings:

Fig. 1 is a plan view of an embodiment of the improved plate, and

Fig. 2 is a cross section on an enlarged scale, taken on the line 2—2 of Fig. 1.

The plate *a* is formed as usual of suitable type metal by electrotyping or other suitable process, and is provided with half-tone or screen-formed printing surfaces *b* and *c*. As customary, the metal at the upper surface of the plate outside of the printing surfaces is cut away.

In the particular embodiment shown, the right-hand edge 10 of the printing surface *c* is formed by or borders on a "high light." To avoid blurring by the edge 10 in the printing operation, the metal of the plate on its under side and beneath the edge 10 is first cut away to form a shallow groove 11. This groove extends laterally as shown on opposite sides of the edge 10. Then pressure is applied to the upper surface of the plate along and closely adjacent the edge 10, but outside of the printing surface, whereby the metal of the plate above the groove is slightly depressed, such depression being indicated in somewhat exaggerated form in Fig. 2. Any suitable means could be employed for slightly depressing the metal of the plate above the groove 11. For example, a blunt tamping tool could be used to apply pressure along a line indicated by the numeral 12 in Fig. 2; or a piece of hard wood could be placed on the plate against the edge 10 of the raised printing surface and then struck lightly with a hammer.

The improved method avoids applying pressure to the printing surface itself or in any way marring such surface, but its edges or edge portion is slightly depressed so that it will not blur in the printing operation. Also, the method is such that a half-tone plate can be very readily and properly corrected to avoid such blurring.

Changes may be made in the details set forth without departure from the scope of the invention as defined in the appended claims.

I claim as my invention:

1. A printing plate provided with a half-tone printing surface and having a groove in its lower face beneath a portion of the edge of the printing surface, the metal of

the plate, along the edge of the printing surface and above the groove being depressed, substantially as described.

5 2. The method of correcting a printing plate which consists in grooving the under surface of the plate beneath an edge portion of its printing surface, and then depressing the metal of the plate above the groove by the application of pressure to the upper face 10 of the plate along and adjacent the edge portion of the printing surface but outside of such surface, substantially as described.

15 3. A printing plate having a groove formed in its flat lower face inside the edge of the plate and extending in part beneath and in part outside an edge portion of the printing surface, the metal of the plate above the groove being depressed, substantially as described.

20 4. The method of treating a printing plate which comprises forming a groove in its flat lower face inside the edge of the plate, and disposed in part beneath and in part outside an edge portion of the printing surface of 25 the plate, and then depressing the metal of the plate above the groove, substantially as described.

30 5. The method of treating a printing plate which comprises cutting a groove in its flat lower face disposed inside of the edge of the plate and beneath at least a portion of the edge of the printing surface of the plate, and then depressing the metal of the plate above the groove by the application of pressure 35 along a line closely adjacent, but outside, the edge portion of the printing surface, substantially as described.

CHARLES G. HAYES.
